[57] **CLAIM**

The ornamental design for a refrigerator/freezer, as shown and described.

DESCRIPTION

FIG. 1 is a perspective view showing a first embodiment of my design from the right front corner and above;

FIG. 2 is a perspective view showing of the design shown in FIG. 1 from the left front corner and above; FIG. 3 is a perspective view showing a second embodiment of my design from the right front corner and above;

FIG. 4 is a perspective view showing of the design shown in FIG. 3 from the left front corner and above; FIG. 5 is a perspective view showing a third embodiment of my design from the right front corner and above; and,

FIG. 6 is a perspective view showing of the design shown in FIG. 5 from the left front corner and above. The bottom and rear of all embodiments of my refrigerator/freezer are plain and nonornamental.
